UNITED STATES PATENT OFFICE.

ROY S. SANFORD, OF SOUTH BEND, INDIANA, ASSIGNOR TO BENDIX BRAKE COMPANY,
OF CHICAGO, ILLINOIS, A CORPORATION OF ILLINOIS.

BRAKE.

Application filed November 2, 1925. Serial No. 66,274.

This invention relates to external contracting brakes, and is illustrated as embodied in a brake for the road wheel of an automobile. An object of the invention is 5 to improve the efficiency of brakes of this type by substituting for the usual flexible band a plurality of shoes of novel form and arrangement.

An important feature relates to overlapping the shoes, by anchoring one shoe between the ends of another, for example by making the one shoe forked at its end and arranging it to straddle the end of the adjacent shoe.

10 Other features relate to an arrangement for insuring successive operation of a pair of connected shoes; to a novel anchor arrangement, and to other new combinations of parts and desirable particular constructions which will be apparent from the following description of one illustrative embodiment shown in the accompanying drawing, in which:

Fig. 1 is a vertical section through the 25 brake, just inside the wheel, showing the brake shoes in side elevation;

Fig. 2 is a section on the line 2—2 of Fig. 1, showing the anchoring of the overlapping shoe ends; and

30 Fig. 3 is a radial section on the line 3—3 of Fig. 1, showing the connection between two of the shoes, and the spring which insures successive operation of the shoes.

In the arrangement illustrated, the brake 35 includes a drum 10, within which may be arranged, if desired, an internal expanding brake 12, and at the open side of which is arranged a backing plate or other support 14.

40 At its lower side, a part of support 14 extends beyond the drum, and carries a pair of anchors 16 and 18, which may if desired pass through reinforcing arms 20 carried directly by the axle. Anchor 16 passes through a relatively large opening 22 in a central shoe 24, and serves as a pivot anchor for arms 26 projecting from the channel-shaped end of a shoe 28 which is T-shaped in cross-section throughout the greater part of its length. Anchor 18, which serves as a pivot for the end of shoe 24 straddled or overlapped by the end of shoe 28, passes through relatively large openings 30 in arms 26.

55 Shoe 24 is illustrated as being T-shaped in cross section throughout its length, and

at its unanchored end is pivotally connected by a pin 32 to arms 34 forming a fork at the end of a T-section unanchored or servo shoe 36. One arm 34 of shoe 36 has a lug 38 projecting laterally beyond backing plate 14, and carrying a headed pin 40 projecting through a bracket 42 secured to the backing plate. A spring 44 sleeved on pin 40 serves as means yieldingly urging the connected ends of shoes 36 and 24 away from the drum, and insuring that shoe 24 will not engage the drum until shoe 36 turns with the drum (counter-clockwise in Fig. 1, the direction of movement of the drum when the vehicle is moving forward) and overcomes the 70 spring.

The brake is applied by suitable means rocking a lever 46 pivoted at 48 to the end of shoe 28, and at 50 to the end of a link 52 passing through a lug 54 on the end of shoe 36 and provided with a threaded adjustable stop 56 engaging the lug. A spring 58 sleeved on link 52 is confined between lug 54 and a fixed bracket 60 secured to the backing plate and having a part turned over at 80 its end and provided with an opening through which link 52 passes.

While one illustrative embodiment has been described in detail, it is not my intention to limit the scope of the invention to that particular embodiment, or otherwise than by the terms of the appended claims.

I claim:

1. A brake comprising, in combination, a cylindrical brake drum, a plurality of brake 90 shoes arranged end to end outside of the drum, and means to anchor one of said shoes between the ends of the adjacent shoe.

2. A brake comprising, in combination, a cylindrical brake drum, a plurality of brake 95 shoes arranged end to end outside of the drum, and means to anchor two of said shoes each between the ends of the other.

3. A brake comprising, in combination, a cylindrical brake drum, a plurality of brake 100 shoes arranged end to end outside of the drum, the shoes having anchoring arms at their adjacent ends out of alinement with and projecting past each other and each projecting past the end of the friction face of 105 the other, and torque-taking means engaged by said arms.

4. A brake comprising, in combination, a cylindrical brake drum, a plurality of brake 110 shoes arranged end to end outside of the

drum, one of the shoes having spaced anchoring arms at its end straddling the end of and projecting past the end of the friction face of the adjacent shoe, and torque-taking means engaged by said arms.

5. A brake comprising, in combination, a cylindrical brake drum, and a plurality of brake shoes arranged end to end and surrounding the outside of the drum, one of the

10 shoes being channel-shaped at least at its end and the adjacent shoe having a part projecting into the channel-shaped end and past the end of the friction face of the channel-shaped shoe.

15 6. A brake comprising, in combination, a cylindrical brake drum, and a plurality of brake shoes arranged end to end and surrounding the outside of the drum, one of the shoes being T-shaped throughout most of its

20 length and channel-shaped at its end and the adjacent shoe having a part projecting into the channel-shaped end.

7. A brake comprising, in combination, a cylindrical brake drum, and a plurality of

25 brake shoes arranged end to end and surrounding the outside of the drum, one of the shoes being channel-shaped at least at its end and the adjacent shoe having a part projecting into the channel-shaped end, past the 30 end of the friction face of the channel-shaped shoe, to overlap the two shoes, together with anchoring means engaged by the overlapping ends of the shoes.

8. A brake comprising, in combination, a 35 drum, a pair of shoes anchored at adjacent ends, a third shoe connected to the unanchored end of one of the pair of shoes, the three shoes being arranged end to end outside of and surrounding the drum, and means for contracting the three shoes upon the drum.

40 9. A brake comprising, in combination, a drum, a pair of shoes anchored at adjacent ends, a third shoe connected to the unanchored end of one of the pair of shoes, the three shoes being arranged end to end outside of and surrounding the drum, means for contracting the three shoes upon the drum, and means yieldingly urging the connected ends of the third shoe and said one of the pair of shoes away from the drum.

45 10. A brake comprising, in combination, a drum, a pair of shoes anchored at adjacent ends, a third shoe connected to the un-

anchored end of one of the pair of shoes, 55 the three shoes being arranged end to end outside of and surrounding the drum, means for contracting the three shoes upon the drum, and means yieldingly urging the connected ends of the third shoe and said one 60 of the pair of shoes away from the drum and yieldingly urging apart the free ends of the third shoe and the other of the pair of shoes.

65 11. A brake comprising, in combination, a drum, a support extending outside the circumference of the drum, a plurality of brake shoes arranged end to end about the outside of the drum, and means for anchoring one end of one of the shoes on said support between the ends of the adjacent shoe.

70 12. A brake comprising, in combination, a drum, a support extending outside the circumference of the drum, a plurality of brake shoes arranged end to end about the outside of the drum, and an anchor for one 75 end of one of the shoes passing through a relatively large opening in the adjacent shoe between its ends and mounted on the support.

80 13. A brake comprising, in combination, a drum, a plurality of shoes arranged end to end outside of and surrounding the drum, anchoring means for the shoes, means for contracting the shoes upon the drum, and means for yieldingly urging the adjacent 85 ends of two of the shoes away from the drum, the three said means being spaced approximately 120° apart.

85 14. A brake comprising, in combination, a drum, a pair of connected shoes arranged 90 end to end outside of the drum, an anchor at the unconnected end of one of the shoes, contracting means at the unconnected end of the other shoe, and a spring arranged to hold the anchored shoe away from the drum 95 until the unanchored shoe moves with the drum and overcomes the spring.

15. A brake comprising, in combination, a drum, a pair of connected shoes arranged end to end outside of the drum, an anchor 100 at the unconnected end of one of the shoes, contracting means at the unconnected end of the other shoe, and a spring arranged to urge the connected ends of the shoes away from the drum.

105 In testimony whereof, I have hereunto signed my name.

ROY S. SANFORD.
